UNITED STATES PATENT OFFICE.

FINN SIMMONS, OF NEW YORK, N. Y., ASSIGNOR, BY DIRECT AND MESNE ASSIGNMENTS, TO THE K & S FURNITURE COMPANY, INC., A CORPORATION OF NEW YORK.

FOLDING STOOL.

1,188,500.

Specification of Letters Patent. Patented June 27, 1916.

Application filed September 11, 1913. Serial No. 789,278.

To all whom it may concern:

Be it known that I, FINN SIMMONS, a citizen of the United States, and a resident of New York, borough of Brooklyn, county 5 of Kings, and State of New York, have invented a certain new and useful Improvement in Folding Stools, of which the following is a full, clear, and exact specification.

10 This invention relates to a class of foldable furniture.

My invention has for its object primarily to provide a folding stool wherein is employed a substantially cross-shaped retaining post to which a plurality of legs are pivoted in a manner so as to be adapted to be hingedly swung radially with respect to the retaining post when the stool is unfolded, or reversely swung toward each other 15 when the stool is folded, and also to said retaining post is pivoted a corresponding number of standards, or supporting members adapted to be hingedly swung upwardly in radial directions with relation to the post for 20 maintaining a flexible seat thereon and which are adapted to be swung downwardly upon the legs when the stool is folded together, each of said standards having a 25 groove longitudinally thereof for reception 30 of one of the legs whereby a compact parcel may be formed to permit the stool to be readily carried by a person from place to place.

Another object of the invention is to provide a flexible seat adapted to be removably applied upon the standards, and which is of a form to permit the seat to serve as a casing for holding the parts of the stool when folded.

40 A further object of the invention is to provide a stool which is susceptible of being made preferably of sheet metal so as to be very light in weight as well as combining great strength and durability.

45 A practical embodiment of the invention is represented in the accompanying drawing forming a part of this specification in which similar characters of reference indicate corresponding parts in all the views, the said 50 invention being more fully described hereinafter, and then pointed out in the claim at the end of the description.

In the drawing, Figure 1 is a perspective view of one form of folding stool embodying my invention. Fig. 2 is an enlarged

vertical longitudinal section taken through the center of the chair. Fig. 3 is an enlarged side elevation showing the stool when folded. Fig. 4 is a top plan of the stool when folded showing the flexible detachable 60 seat when wrapped therearound to serve as a casing, and Fig. 5 is an inverted plan of the flexible seat of the stool.

The folding stool has a retaining post 10 provided with a body portion 11, and extending radially from the body portion in the type of a cross are four lugs, or ears 12, 13, 14, 15, all of which may be of suitable heights. Guided through an opening provided transversely in the lower parts of each 70 of the lugs 12, 13, 14, 15 is a pin, or bolt, as 16, all being of sufficient lengths to extend a slight distance laterally beyond the side surfaces of the lugs, and upon said bolts are pivoted the upper ends of four legs, as 17, 75 18, 19, 20.

All of the legs, 17, 18, 19, 20 are similar in formation, and each of these legs is made preferably of sheet metal which is bent in substantially the shape of an inverted U, as viewed transversely, to provide two depending flanges 21 and 22, and a bridging strip 23 longitudinally thereof, whereby the legs may be light in weight, but may be of the required strength. The 80 upper end portions of the legs 17, 18, 19, 20 are slightly curved, as at 24, and the parts of the flanges 21 and 22 at these curved portions are pivotally held upon the bolts 16 so that the curved portions of the legs 90 are disposed in straddle arrangement upon the lugs. In this manner the legs 17, 18, 19, 20 are adapted to be hingedly swung outwardly in radial directions with respect to the retaining post 10 when the stool is unfolded, and by pivoting the legs to the lower parts of the lugs of the retaining post, the upper edges of the bridging strips 23 of the legs will abut against the lugs so as to serve for limiting the outward movement of the 100 legs when the stool is in use. Also pivoted to the bolts 16 of the lugs of the retaining post 10 are the lower ends of four standards, or supporting members 25, 26, 27, 28, all of which are similarly formed. Each 105 of the standards 25, 26, 27, 28 is preferably made of sheet metal which is bent lengthwise in approximately the shape of an inverted U, as viewed transversely, to provide two depending flanges 29 and 30, and 110

a bridging strip 31 longitudinally thereof. A groove 32 is thereby provided longitudinally of the underside of each standard, and all of said standards are made of sufficient 5 widths so that each leg of the stool will be received in one of the grooves of the standards when the stool is folded together. The lower end portions of the bridging strips 31 are somewhat shorter in length than the 10 flanges 29 and 30 of the standards so as to provide the flanges of each standard with two spaced ears, or extensions, as 33 and 34. The ears 33 and 34 of each standard are pivotally held upon one of the bolts 16 15 so that the curved end 24 of each leg extends therebetween. The standards will thereby be also disposed in straddle arrangement upon the lugs of the retaining post 10. When the stool is unfolded for use the 20 standards 25, 26, 27, 28 are hingedly swung upwardly in radial directions with relation to the retaining post 10, and the lower free end of the bridging strip 31 of each standard will rest against the curved end of the 25 leg disposed between the ears of the standard so as to limit the upward movement of the legs.

In conjunction with the stool, I provide a separate seat, as 35, which may be of canvas, or other flexible material, and may serve as a covering for parts of the stool when not in use. The seat 35 is substantially square, and upon the corners of the seat are provided hooks, as 36, 37, 38, 39, 30 and these hooks are preferably made of metal. When the standards 25, 26, 27, 28 and the legs 17, 18, 19, 20 are adjusted for using the stool, as above described, the seat is applied upon the upper ends of the standards so that hooks 36, 37, 38, 39 may be guided over and into engagement with the free ends of the bridging strips 31 of the standards. To fold the stool the seat is 40 detached from the standards by removing 45 the ends of the bridging strips thereof from the hooks of the seat. The legs are then folded together, and the standards are swung thereupon, after which these parts are wrapped in the seat 35, the free end of

which may be detachably fastened to the 50 body portion thereof by any suitable forms of hooks and eyes, or otherwise.

In the foregoing description, I have embodied the preferred form of my invention, but I do not wish to be understood as limiting myself thereto, as I am aware that modifications may be made therein without departing from the principle, or sacrificing any of the advantages of this invention, therefore I reserve to myself the right to 55 make such changes as fairly fall within the scope of the appended claim.

Having thus described my invention, I claim as new and desire to secure by Letters Patent:—

A folding stool, consisting of a post with four quadrangular lugs extending radially, at right angles therefrom, four corresponding legs of inverted U-shapes in cross-section each having its upper portion pivoted to one of the lugs in straddle arrangement so that all of the legs may be swung inwardly and outwardly relatively to the vertical center of the post, and the upper end of each leg above its pivot being rounded 70 and bent outwardly at an obtuse angle for the intermediate part of the bent portion to contact with the lug whereby the outward movement of the legs will be limited, four similar standards of inverted U-shapes 75 in cross-section each with its lower portion pivoted to one of the lugs in straddle arrangement on one of the legs and the intermediate part of the pivoted portion of each standard being cutaway so that the 80 standards may be swung radially upward 85 above the post as well as to and from overlapping positions on the standards, and a flexible seat with four quadrangularly arranged hooks for being removably guided over the upper ends of the standards when 90 swung above the post.

This specification signed and witnessed this tenth day of September, A. D. 1913.

FINN SIMMONS.
